UNITED STATES PATENT OFFICE.

HENRY A. MEYER, OF HELENA, MONTANA.

SEPARABLE FASTENER.

1,083,372.

Specification of Letters Patent.

Patented Jan. 6, 1914.

Application filed February 24, 1913. Serial No. 750,314.

To all whom it may concern:

Be it known that I, HENRY A. MEYER, a citizen of the United States, residing at Helena, in the county of Lewis and Clark 5 and State of Montana, have invented certain new and useful Improvements in Separable Fasteners, of which the following is a specification, reference being had to the accompanying drawings.

10 This invention relates to new and useful improvements in buttons and more particularly to that class known as separable fasteners, the object of the invention being to provide a button comprising two parts, each 15 of which are secured to separate pieces of material whereby the said pieces of material may be quickly and easily fastened together and securely held in set position.

Another object of the invention is to provide a button of the above character whereby 20 two pieces of material may be securely fastened together and which will not only hold the material in position, but can be quickly and readily released.

25 A further object of the invention is to provide a button of the above character which will possess advantages in points of efficiency and durability, is inexpensive of manufacture and at the same time is simple 30 in construction and operation.

With the above and other objects in view, the invention consists in the novel features of construction and the combination and arrangement of parts to be hereinafter more 35 fully described, pointed out in the claim and shown in the accompanying drawings, in which—

Figure 1 is a top plan view of the button; Fig. 2 is a transverse sectional view of the 40 same; Fig. 3 is a top plan view of the fastening member; Fig. 4 is a similar view showing the movable plate in its open position; and Fig. 5 is a transverse sectional view of the fastening member, the button being shown in dotted lines in its second position.

Referring more particularly to the drawings, 1 indicates the button, which is provided with an annular base flange 2 having 50 a plurality of circularly arranged openings 3 formed therein by means of which the button is secured to the material. Projecting outwardly from the base flange 1 is the shank 4 having a suitable head 5 formed at 55 the outer end thereof and provided with the shoulders 6 against which the fastening

member 7 is adapted to securely fasten two pieces of material together. The fastener 7 is to be secured to a separable piece of material and comprises a circular body member 60 8 which is provided at its upper edge with an outwardly projecting flange 9 having a plurality of openings 10 formed therein, whereby the same may be secured to the material with any suitable fastening means. Arranged in spaced relation with the flange 9 and secured thereto by means of the rivets 11 is a ring 12. Arranged between the ring 12 and the flange 10 at one side of the body 8 is a substantially triangular shaped plate 13, 70 said plate being held rigidly in place by means of the rivets 11, and the apex thereof, which extends inwardly toward the center of the opening 14 formed by the ring 12, is cut away to provide a curved recess 15 75 adapted to receive the shank 4 of the button 1. Arranged in opposed relation with the plate 13 is a movable plate 16, said plate being disposed between the ring 12 and the flange 10 and pivotally secured at one corner 80 by means of the pin 17. The plate 16 is of substantially triangular shape and the apex thereof, which projects inwardly toward the center of the opening 14 is provided with a curved recess 15' adapted to receive the shank 85 of the button 1. The corner of the plate 16 opposite the pivot pin 17 is provided with a lug 18, which is adapted to be engaged by the finger nail or other object to swing the plate outwardly from the opening 14 to release the head 5 of the button. 90

In the practical operation of my improved device, the button 1 and the fastener 7 are applied so that they are disposed in opposed relation. The fastener 7 is engaged with 95 the button by moving the plate 16 outwardly and passing the head of the button into the body 8 so that the shank 4 is disposed within the recess 15 formed in the rigid plate 13. The plate 16 is then swung to its locked position, as shown in Fig. 3, so that the apexes of the two plates are engaged beneath the shoulder 6 which will absolutely prevent the removal of the head 5 from the fastener. When it is desired to release the button, the 100 plate 16 is swung outwardly by engaging the lug 18 with any suitable object.

From the above it will be seen that separable material to which my improved device is secured, may be quickly and readily fastened together or quickly released. It will 105 also be apparent that the device is extremely 110

simple in construction and can be manufactured at a comparatively low cost.

While I have shown and described the preferred form of my invention, it will be 5 obvious that various changes in the details of construction and in the proportions may be resorted to for successfully carrying my invention into practice without sacrificing any of the novel features or departing from 10 the scope of the appended claim.

What I claim is:—

A separable fastener including a headed button and a fastener comprising a circular body member adapted to receive the head of 15 a button, an annular flange formed upon said body and provided with a plurality of openings; a ring secured to the flange and arranged in spaced relation therewith, a rigid and a movable plate disposed in a hori-

zontal position and arranged in opposed relation, said plates being of substantially triangular form and having their apexes projecting inwardly toward the center of the ring, the apexes of said plates being provided with curved recesses to receive the 25 shank of the headed button, the apexes of said plates being arranged directly above the center of the circular body and said movable plate being adapted to detachably engage the head of the button to retain the same 30 within the body.

In testimony whereof I hereunto affix my signature in the presence of two witnesses.

HENRY A. MEYER.
